UNITED STATES PATENT OFFICE.

WILLIAM MARCUS LOW, HORN, OF SUMMERTOWN, TENNESSEE.

WINDOW LOCK.

1,424,107.

Specification of Letters Patent. Patented July 25, 1922.

Application filed January 11, 1922. Serial No. 528,891.

To all whom it may concern:

Be it known that I, WILLIAM LARCUS LOWTHORN, a citizen of the United States, residing at Summertown, in the county of Lawrence and State of Tennessee, have invented a new and useful Window Lock, of which the following is a specification.

This invention aims to provide a simple means whereby a window or the like may be held at adjusted heights, it being possible to raise the window, to lower the window, to hold the window at any desired height, to be moved upwardly when desired, and to lock the window, so that the same cannot be moved either upwardly or downwardly. Another object of the invention is to provide a device of the class described which will possess great strength, and be well adapted to withstand the efforts of persons seeking to raise the window with felonious intent.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:-

Figure 1 shows in elevation, a device constructed in accordance with the invention, parts being in section; Figure 2 is a longitudinal section taken through the guide which carries the locking bolt; and Figure 3 is a section on the line 3-3 of Figure 1.

The numeral 1 marks a window frame, the numeral 2 designating a window sash carrying a pane 3. A rack strip 4 preferably made of metal is secured at 5 to the frame 1 and has any desired number of rectangular seats 6, including parallel horizontal portions 7.

A tubular guide 8 is provided and has flanges 9 through which securing elements 10 pass, the securing elements serving to hold the guide or the sash 2. In the guide 8 a T-shaped slot 11 is formed, the slot including a body 12 extended transversely of the guide, and a head 14 extended longitudinally of the guide, the body portion 12 of the slot having an arm 15 extended longitudinally of the guide and opening through the inner end thereof, as clearly shown in Figure 1. A bolt 16 is mounted for reciprocation in the guide 8 and has a stud 17 provided with a finger piece 18 of any desired kind. The stud 17 extends outwardly through the slot 11 in the guide 8 and is adapted to operate therein as hereinafter described. At its outer end, the bolt 16 terminates in a tip 19 having a beveled extremity, and provided with parallel sides 21. A compression spring 22 is located in the guide 8 and is interposed between the end of the bolt 16 and the end of the guide.

When the parts are arranged as shown in Figure 1, the bolt 16 is advanced by the spring 22 until the stud 17 abuts against the casing 8 at the outer end of the head 14 of the slot 11, the beveled end 20 of the tip 19 of the bolt being so positioned with respect to the seat 6 that, when the sash 2 is raised, the bolt 16 will slide to the right (Figure 1) and permit a raising of the sash. The tip of the bolt cooperates with the seat 6 in such a way that, as will be evident from Figure 1, the window sash 2 cannot be lowered until the bolt 16 is moved to the right, the stud 17 retiring into the right hand end of the head 14 of the slot 11. When the parts are arranged as shown in Figure 1, the window sash 2 is held releasably against downward movement, but is free for upward movement.

Through the instrumentality of the stud 17, the bolt 16 may be given a quarter turn, the stud 17 traversing the body 12 of the slot 11 and moving into the arm 15 of the slot. Under such circumstances, the parallel sides 21 of the bolt cooperate with the parallel portions 7 of the seat 6, and, then, the window sash 2 is locked positively against movement either upwardly or downwardly. Since the arm 15 of the slot extends through one end of the guide 8, the bolt 16 may be inserted into the guide, the stud 17 entering through the arm 15 of the slot.

It is to be observed that the guide 8 includes a thickened portion 25, wherein the major portion of the slot 11 is located. Owing to the fact that the guide is thickened as at 25, the guide is not materially weakened by the formation of the slot. The flanges 9, further, are carried by the afore-

said thickened portion 25 of the guide and the strength of the device is enhanced, so far as the attachment of the guide to the window sash is concerned.

5 What is claimed is:—

1. The combination with a frame and a slideable sash, of a rack strip on the frame and having a seat provided with parallel portions; a guide on the sash and having a T-shaped slot including a transverse body, a longitudinal head at one end of the body and a transverse arm at the other end of the body; a bolt slideable in the guide, and a stud projecting from the bolt, the bolt co-
10 operating with one of the parallel portions of the seat to hold the sash against downward movement and the bolt having a beveled end which is so positioned with respect to the other parallel portion of the seat that
15 the sash may be raised when the stud is at one end of the head of the slot, the stud being movable to the other end of the head of the slot to permit a lowering of the sash, the bolt having parallel surfaces, and being
20 rotatable to permit said surfaces to coact
25

with the parallel portions of the seat thereby to hold the sash against upward movement and downward movement, the stud being adapted to enter the extension of the slot by way of the body of the slot, thereby to 30 hold the bolt against rotation; and spring means in the guide for advancing the bolt.

2. A device of the class described, constructed as set forth in claim 1, and further characterized by the fact that the extension 35 of the slot opens through one end of the guide.

3. A device of the class described, constructed as set forth in claim 1, and further characterized by the fact that the guide in- 40 cludes a thickened portion wherein the major part of the slot is located, said thickened portion carrying flanges whereby the guide is attached to the sash.

In testimony that I claim the foregoing as 45 my own, I have hereto affixed my signature in the presence of a witness.

WILLIAM MARCUS LOWTHORP.

Witness:

ERNEST WRIGHT.
